Primary Examiner — Mary Ann Calabrese

(57) **CLAIM**

The ornamental design for a display holder for attachment to garments and accessories, as shown and described.

DESCRIPTION

FIG. 1 is a perspective view of a display holder for attachment to garments and accessories, showing a label inserted; FIG. 2 is another perspective view of display holder for attachment to garments and accessories showing my new design;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken line showing of a label is included for the purpose of illustrating environmental structure and forms no part of the claimed design.

1 Claim, 8 Drawing Sheets
